UNITED STATES PATENT OFFICE

JAMES CONRAD, OF ROXBURY, MASSACHUSETTS

DESIGN FOR A LAMP SHADE

Application filed February 3, 1932. Serial No. 42,721. Term of patent 7 years.

To all whom it may concern:

Be it known that I, JAMES CONRAD, a citizen of the United States, residing at Roxbury, in the county of Suffolk and State of Massachusetts, have invented a new, original, and ornamental Design for a Lamp Shade, of which the following is a specification, reference being had to the accompanying drawings, forming part thereof.

Figure 1 represents a plan of a lamp shade showing my new design.

Figure 2 represents a front elevation of same.

Figure 3 represents an elevation of the left end of same, and

Figure 4 represents an elevation of the right end of same.

The rear of the lamp shade is substantially plain.

I claim:

The ornamental design for a lamp shade as shown and described.

JAMES CONRAD.
